CLOSURE

Bruno von Bültzingslöwen, New York, N. Y.

Application September 24, 1934, Serial No. 745,274

20 Claims. (Cl. 221—60)

This invention concerns a closure for containers and is hereinafter exemplarily illustrated as a cap for collapsible tubes and bottles.

One object of this invention is to provide a simple closure or cap for containers which remains on the container at all times, whether the container is open or closed, so that the cap or closure is not lost.

A second object of this invention is to provide a closure for a container which allows adjustments between the open and closed positions, so that there are intermediate partially open positions, controlling the dispensation at will.

A third object of this invention is to provide a double closure of the channels through which dispensation takes place. More particularly, in connection with dispensing necks, an inner as well as an outer closure for the dispensing opening are comprised in one cap.

20 A further object of this invention is to provide a closure in which the container or an extension thereof or the closing means are in slidably abutment at substantially all points, so that a relatively thin material may be used for the various 25 parts, the various thin layers of abutting parts reenforcing each other.

Still another object of this invention provides for an enclosure which may be manipulated with extreme ease, so that the container as well as the 30 opening and closing thereof may be brought about by manipulation with one hand only, the other hand of the user being free to be used otherwise.

Another object of this invention is to provide a slidable means on a container, which provide a 35 double or triple closing, so that not only liquids, but also fluids generally, for instance aromatic liquids, may be kept in such containers, ready for instant use and still tightly closed.

A further object of this invention is to have, in 40 connection with a cap which provides a double closure, means displacing on the closed container the fluid to be dispensed from all voids of the closure which it may fill while the closure is open.

Additional objects shall be brought forth and 45 will be more readily understood from the following description and the accompanying exemplary illustrations, of which:—

Figs. 1 and 2 show collapsible tubes closed by closures or caps of my invention, the former being directed to an arrangement with a control by rotation, the latter a modification in which the closing is controlled by reciprocating the cap.

Figs. 3, 4, 5 and 6 are detailed sections corresponding to the showing of Fig. 1:

55 Fig. 3 shows the closure in a closed position and

is the top view of a cross-section at a level indicated by a dot-dash line and by numeral 3 in Fig. 5.

Fig. 4 is a corresponding view in which the closure is open.

Figs. 5 and 6 are cross-sectioned elevations of the upper end of the closed and open container, respectively.

Fig. 9 shows an elevation of the upper end of the container of Figs. 1 and 3 to 6, without the cap or closure.

Figs. 7, 8 and 10 to 12 relate to the modification shown in Fig. 2:

Figs. 7 and 8 show cross-sectioned top views of the closed and open container, respectively, said cross-sections being taken along lines identified by the numerals of said figures in Figures 10 and 11.

Figs. 10 and 11 are sectional elevations corresponding to the positions of Figs. 7 and 8, respectively.

The cross-section of Fig. 12 is similar to that of Fig. 10, but shows a modified shape of the cap.

Fig. 13 is the elevation of a bottle provided with my closure.

Figs. 14 and 15 show cross-sectioned elevations of the upper end of such a bottle, the closure being in an open position in the former and closed in the latter figure.

Figs. 16 to 19 serve to illustrate another modification of my invention:

Figs. 16 and 17 are cross-sectioned elevations in which the closure is in a closed and opened position, respectively.

Fig. 18 is a side view of a plug used in the modification of Figs. 16 and 17.

Fig. 19 shows a front view of the neck of the respective container.

Figs. 20 to 24 illustrate containers and caps or closures of my invention which may be rotated and as well may be moved axially relatively to the container.

Figs. 20 and 21, respectively, show the cross-sectioned elevation of a modified closure in a closed and open position; the cap moves along a spiral path when opened or closed. In Fig. 20, holes 85 are omitted.

Fig. 22 shows a side view of the neck of the bottle of the modifications of Figs. 20 and 21.

Figs. 23 and 24 show, in similar views, necks, which are provided with various guide grooves.

Figs. 25 and 26 show, in open and closed positions respectively, cross-sectioned elevations of another modification of my invention, which provides an extension on the container; that ex-

tension cooperates with the closure and forms part thereof.

Similar numerals refer to similar parts throughout the various views.

5 Figs. 1 and 2 exemplarily show collapsible tubes 31 and 32 which are executed substantially according to present-day practice in this art, except that the respective necks 33 and 34 are particularly shaped in accordance with my invention. Upon the necks 33 and 34 of the containers of Figs. 1 and 2 are applied the closures 35 and 36, respectively. Figs. 3 and 4 show the cap 35 to be depressed at one point, and the resulting indentation 37 extends into a substantial-
10 ly semi-circular groove 38 provided in the neck 33.

15 At one side the cap 35 is perforated by an opening 39 which is shown to be circular but which may assume any shape preferably suited for the dispensation of the contents of the container or collapsible tube 31.

20 The cap 35 is arbitrarily indicated to be slidably rotatable through substantially 180° upon the neck 33; the extent to which said cap may be rotated is determined by the length of the groove 38, the ends of which serve as stops for the indentation 37 of cap 35. At one extreme position (Figs. 4 and 6) of rotation of cap 35, the opening 39 in the cap 35 registers with an opening 40 in the neck 33. If the opening 39
25 is disposed substantially at the level of the upper part of the neck 33,—as it is exemplarily shown in the drawings,—then the opening 40 may assume the shape of a notch (Fig. 9), extending down into the neck 33.

30 In the cap 35 is fixedly mounted a hollow or solid core or plug 41, the upper end of which, the head 42, forms part of said cap or substantially fits diametrically into the cap 35, abuts upon the bottom of said cap, which is suitably
35 fastened therein, for instance by the dents 43 of said cap, which are depressed into corresponding indentations in the head 42, so that the cap and plug are in a relatively fixed position. The head 42 abuts upon the neck 33, and an
40 extension, a stem 44, depends in slidable abutment from the head 42 into the opening of the neck 33. The stem 44 is provided with a recess 45, which downwardly opens into the container and which also issues through one side of the stem
45 in registering alignment with the opening 39 in cap 35. It will be understood that the groove or recess 45 also registers with the opening or notch 40 in the neck 33 of the container, when the cap or closure 35 is in the open position
50 of Figs. 4 and 6. But in the closed position of Figs. 1, 3 and 5, the recess 45 is laterally closed by the wall of neck 33, and in that position said wall also closes the opening 39 of the cap; whereas in that same position the opening or notch
55 40 in the neck 33 is closed at one end and at the top by the stem 44 and the head 42 of the plug 41, respectively, and at the other end by the wall of the cap 35. A double closure of the container or collapsible tube 41 is therefore provided for as soon as the opening 39 and groove
60 45 on one hand, and the opening and notch on the other hand have been shifted out of registering alignment.

65 Whereas in the arrangement of Figs. 1, 3 to 6 and 9 the cap 35 is rotated from an open into a closed position and vice versa, the cap 36 of Fig. 2 is slid up and down, or axially reciprocated for the purpose of opening and closing the closure. This is illustrated in detail in Figs. 7 and 10, and Figs. 8 and 11, which show such

an arrangement in a closed and open position, respectively.

70 In analogy to the arrangement of the prior modification, the cap 36 with perforation 46 is exemplarily attached by the dent 47 upon indentations in the head 49 of the plug 48, but the stem 50 of plug 48 and the cylindrical part of cap 36 are longer, in order to bring about a double closing in the covered position of the cap of Figs. 7 and 10 and in order to provide 10 the necessary mechanical guidance in the raised and open position of Figs. 8 and 11.

75 The neck 34 of the container or collapsible tube 32 is provided with longitudinal (vertical) groove 51 in which is slidably disposed the depressed dent 52 of the cap 36. The recess or groove 53 in the stem 50 registers with the opening 46, and they both are closed by the neck 34 in the position of Fig. 10. In the open position of Fig. 11, in which the cap 36 is raised, the opening 20 46 and opening, groove or recess 53 register with a hole or opening 54 extending through the wall of the neck 34 so that in that position the contents of the container or collapsible tube may be dispensed.

25 The modification of Fig. 12 corresponds in respect to most details with the modification just described, but the plug 48 is provided with a differently shaped head 55, said head exceeding in diameter the diameter of the neck 34. Correspondingly, the cap 56 of this modification is bulged out at the bottom to fit around said large head 55 of the plug 48, thus offering a knob-like part, which facilitates engagement and gripping of the cap for the purpose of manipulation in 35 the opening and closing operations. Of course the upper part of the plugs 41 or 48 may thus be shaped at will, and the outer surface of the cap may be variously adapted, e. g., by knurling, to such purpose or for purposes of adorn- 40 ment.

While I reserve the right to apply any materials for the various parts of my invention, the selection of which,—for the cap, plug and also for the neck of the container,—suggests itself 45 to those versed in these arts, it is understood that certain materials prove particularly useful on account of economic or manufacturing considerations. While the cap is preferably made of metal and preferably drawn or stamped and 50 may thus be executed very thinly, I find certain mouldable materials, e. g., condensation products, to be very useful for the plug. Of course the materials should be chosen so as not to corrode or swell under the influence of the fluids accom- 55 modated in the container.

While collapsible tubes ordinarily are made of metal, and therefore the neck thereof might also be made of metal, there are many containers, e. g., bottles, in connection with which glass is 60 the mostly used material. For that reason the containers in the remaining figures are indicated to be executed in glass.

While glass containers at the present state of development of the arts may be moulded very 65 close to the desired dimensions, it may be preferable to provide in connection with glass, as well as with the containers, several steps, for instance on the inside of the neck 61 of a bottle 62, so that a closure at one or the other point, 70 either in peripheral slidable abutment or in end- wise axial abutment is assured. The stem 63 of the plug 64 used in connection with such a bottle may accordingly be recessed at 65 near its lower end, the interior of the neck 61 of the 75

bottle being correspondingly widened out, upward from shoulder 66, in order to accommodate the wider shank 67 at the upper end of stem 63. The plug 64 may again be secured by an indentation 68 in a cap.

5 A groove 70 extending around part of the neck 61 of the bottle 62 serves to guide the circular movement of the cap and the radial hole 71 in stem 63 merges with an axially disposed hole 72, 10 registers with the hole 73 in cap 69, and may be shifted into alignment with the hole 74 extending through the wall of the neck 61 when fluid contents of the bottle are to be dispensed.

When it is desirable to provide a container in 15 which all contents, remaining in the container when not in use, are separated from the outside by a double closure, such a void as occurring in the prior arrangements at 40, 54 and 74 may be eliminated by combining with the closure 20 a part which fills said void when the bottle is closed. Such a part is indicated at 76 in Fig. 18, representing a key, which forms part of the stem 63 and which matches a square notch 77, provided at the upper end of the neck 25 61 of the container.

If the cap 69 of such an arrangement is to be retained at all times upon the bottle, an indentation 78 and a longitudinal (vertical) groove 79, corresponding to the arrangement of 30 Figs. 7, 8, 10 and 11, may be provided for, and the head may of course assume any preferred shape like that of Fig. 12.

Since the notch 77 is shown to be rectangular, and since the key 76 is correspondingly shaped, 35 the dispensing opening 80 in cap 69 may also be shaped oblong or square, so that the contents of the container may be dispensed in a preferably shaped jet, and the cross-section of said jet is varied according to the height to which the 40 cap is adjusted during dispensation.

The guide groove in the neck of the bottle, which determines the path along which the cap is moved for the purpose of opening and closing the container, may of course be variously disposed. The groove 83 of the modification of Figs. 45 20, 21 and 22 is for instance helically disposed so that the cap does not only rotate, but also moves up and down during opening and closing; such an arrangement entails various advantages; thus for instance an arrangement of this kind 50 will tend to avoid a binding of the parts upon each other because they peripherally as well as axially slide upon each other. When the groove 83 is disposed at an angle of 45°, and the dispensing opening 84 is square, the jet dispensed will always be square when the closure is fully or partly 55 opened, just as such a square jet will always be provided for if the openings of the prior modifications are diamond-shaped.

50 A dispensation by way of a plurality of jets may readily be provided for; and for other purposes, a plurality of openings may be doubly closed by means of my invention, or such additional openings may be provided for in order 60 to vent the voids which are enlarged or disappear during the opening or closing of the container.

70 Thus for instance it may be desirable to provide a vent on the bottle by which air may enter into a bottle when a liquid is dispensed, so that the fluid contained in the container may be dispensed at an even flow. Such an opening or hole 85 is indicated in Fig. 21, said opening extending in the open position of the bottle through the

cap, neck and stem, into the groove 86 in said stem.

In connection with the modification of Figs. 16 to 19 the guide groove 79 may be omitted. In that case the closure may be opened and closed 5 and may also be freely removed from the container. In order to provide for such removal in connection with containers using my invention in other modifications, and for instance where the container is to be conveniently refilled, I 10 may provide angular extensions of the guide grooves.

The groove 88 on the neck 61 of Fig. 23 is for instance provided with a vertical extension 89 at one end, which clears the indentation 37 15 guided in groove 88 so that the cap may be removed. Such an extension may be provided in connection with grooves 38 or 70. Where there is a vertical groove 90, like groove 51 of Figs. 10, 11 and 12, said groove may be extended to the 20 right by a section 91 and then I may again provide a vertical section of a groove 92 connecting with the end of section 91; thus the indentation of the respective cap may be moved from a closed position at the bottom of groove 90 to an open 25 position at the top end of said groove, as before, and vice versa; but then the indentation may be swung at the said top level to the right along groove section 91, and along section 92 out of engagement with the neck of the bottle, whereby 30 the cap is removed from the bottle.

It will be readily seen that a separate extension 94 may be provided upon the bottle, which is tightly beaded at 95 over a rim 96 encircling the neck 61 and which forms an extension in 35 the shape of a sleeve above the top of the neck of the bottle and which wholly or partly abuts upon the shiftable closure. In connection with this arrangement I also show a variation in the arrangement which serves to engage the closure 40 upon the container so that it cannot be removed. Instead of providing an indentation in the outer cap which engages upon a groove in the container, I here show an indentation 97 in the extension 94 which is slidably engaged upon a 45 groove 98 extending around plug 99. The plug 99 may of course be completely disposed on top of the container neck 61 proper, or a stem extension 100 may depend therefrom into the neck of the bottle or container, and engage upon the 50 inside of the neck of the container in slidably abutment. It will be seen from Figs. 25 and 26 that this arrangement allows the channel or opening 101 between the outer cap 102 and the plug 99 to be made extremely short, because the 55 extension 94 may be a thin sleeve.

The converse, concentric sleeves extending from a container, a single cap extending therebetween and suitable openings extending through said sleeves and cap within the meaning of this 60 invention, suggests itself to those skilled in these arts. Therefore this invention is not limited in scope to the exemplar showings disclosed but I desire full protection within the following claims.

65 I claim:

1. In a container, a wall with an opening extending therethrough, a closure longitudinally slidably abutting upon both sides of said wall and closing both ends of said opening, and registering openings in said closure on opposite sides of said wall, said closure being slidable on said wall into a position in which the openings in the closure and in the wall register with each other. 70

2. In a container, a wall with an opening ex- 75

- tending therethrough, a closure longitudinally slidably abutting upon both sides of said wall and closing both ends of said opening, registering openings in said closure on opposite sides of said wall, said closure being slidable on said wall into a position in which the openings in the closure and in the wall register with each other, and means guiding said closure on said wall between a position in which the openings in said closure register with said openings in said wall and a position in which said closure closes the ends of the opening in said wall and said wall closes said openings in said closure.
3. In combination with a container a closure therefor, comprising relatively fixed concentric parts, and a sleeve opening from said container and longitudinally slidably fitting between said parts, said parts and sleeve being perforated and the perforations registering with each other and forming an outlet from said container when said closure and sleeve are predeterminedly aligned.
4. In combination with a collapsible tube a closure therefor, comprising relatively fixed concentric parts, and a sleeve forming part of said collapsible tube and longitudinally slidably fitting between said parts, said parts and sleeve being perforated and the perforations registering with each other and forming an outlet from said collapsible tube when said closure and sleeve are predeterminedly aligned.
5. In combination with a bottle a closure therefor, comprising relatively fixed concentric parts, and a neck on said bottle and longitudinally slidably fitting between said parts, said parts and neck being perforated and the perforations registering with each other and forming an outlet from said bottle, when said closure and neck are predeterminedly aligned.
6. In combination with a container a closure therefor, comprising relatively fixed concentric parts, and a sleeve longitudinally slidably fitting between said parts, means guiding the relative movement of said closure and sleeve, and openings in said sleeve and said parts and forming an outlet for said container when said sleeve and closure are relatively moved into a predetermined position.
7. In combination with the neck of a container, a closure comprising a cap longitudinally slidably fitting over said neck, a stem depending from said cap and slidably fitting into said neck, means movably retaining said closure on said neck, relatively registering openings in said cap and stem, and an opening in said neck normally closed by said cap and stem but registering with said registering openings when said closure and neck are relatively moved into a predetermined position.
8. In combination with the neck of a container, a closure comprising a cap longitudinally slidably fitting over said neck, a stem depending from said cap and slidably fitting into said neck, means longitudinally movably retaining said closure on said neck, relatively registering openings in said cap and stem, and an opening in said neck normally closed by said cap and stem but registering with said registering openings when said closure and neck are relatively moved into a predetermined position.
9. In combination with the neck of a container, a closure comprising a cap longitudinally slidably fitting over said neck, a stem depending from said cap and slidably fitting into said neck, means rotatably retaining said closure on said neck, relatively registering openings in said cap and stem, and an opening in said neck normally closed by said cap and stem but registering with said registering openings when said closure and neck are relatively moved into a predetermined position.

and stem, and an opening in said neck normally closed by said cap and stem but registering with said registering openings when said closure and neck are relatively moved into a predetermined position.

10. In combination with the neck of a container, a closure comprising a cap slidably fitting over said neck, a stem depending from said cap and slidably fitting into said neck, means guiding said closure on said neck along a helical path of sliding movement, relatively registering openings in said cap and stem, and an opening in said neck normally closed by said cap and stem but registering with said registering openings when said closure and neck are relatively moved into a predetermined position, the lead of said helical path exceeding the extent of said opening in an axial direction.

11. In combination with a neck extending from a container, a closure longitudinally slidably extending over, onto and into said neck, a groove in said neck, a protuberance extending from said closure into said groove, slidable therein and guiding said closure relatively to said neck between an open and closed position, and openings in said neck and in said closure registering with each other in said open position.

12. In combination with a neck extending from a container, a grooved closure longitudinally slidably extending over, onto and into said neck, a groove in said closure, slidable therein and guiding said closure relatively to said neck between an open and closed position, and openings in said neck and in said closure registering with each other in said open position.

13. In combination with a container, a neck extending from said container and perforated on opposite sides, and a closure slidably abutting upon the inside and outside of said neck and normally closing said perforations, said closure being provided with perforations registering with the inner and outer ends of said perforations in said neck when it is predeterminedly aligned on said neck, sets of said aligned perforations providing a fluid outlet and an air inlet on said container.

14. In combination with a neck of a container, a closure longitudinally slidably extending into, and over said neck, means predeterminedly guiding said closure on said neck between extreme positions in which said container is open and closed, and an opening extending in the open position of said closure from the outside through said closure, said neck and again through said closure into the inside of said container.

15. In combination with a neck on a container, a closure longitudinally slidably extending over the outer and inner faces of said neck, a groove in said neck, and an indentation in said closure extending into said groove in said neck and guided therein.

16. In a combination with a neck on a container, a closure slidably extending over the outer and inner faces of said neck, a groove in said neck, an indentation in said closure extending into said groove in said neck and guided therein, and an angular extension of said groove opening from the end of said neck and facilitating the removal of said closure from said neck.

17. On a container, a neck section and a closure section in longitudinally slidable abutment, the closure section covering the inside, end and outside of said neck section, a guide groove on one of said sections, and a protuberance on the other section extending into said groove, and a hole

extending through said sections and opening from the inside of said container to the outside, the part of said hole in said neck section being closed at both ends by said closure section, when the relative position of said sections is predeterminedly changed.

5 18. In a container, a wall with an opening extending therethrough, a closure slidably abutting upon both sides of said wall and closing both ends of said opening, and a part comprised in said closure and surrounded by said wall and provided with a recess extending from an edge between two adjacent faces of said part, where one of said faces abuts upon said wall and the other 10 fronts the inside of said container.

10 19. In combination with a container, a neck extending from said container and perforated on opposite sides, a closure slidably abutting upon the inside and outside of said neck and normally closing said perforations, said closure being provided with perforations registering with the inner and outer ends of said perforations in said neck when it is predeterminedly aligned on said neck, sets of said aligned perforations providing a fluid 15 outlet and an air inlet on said container, and means for guiding said closure on said neck in a movement between the position where said closure closes said perforations and said position of

predetermined alignment and for permitting removal of said closure from said neck from said position of alignment in a direction angular to that of said guided movement.

20. A container, comprising a cylindrical wall 5 forming a neck and having a round hole extending transversely through said neck, a groove of limited length extending upon the outside of said neck, a closure having an outer cylindrical part and a core respectively slidably fitting the outside 10 and the inside of said neck, and an indentation in said cylindrical part of said closure, extending into said groove and guiding said closure upon said neck between two extreme positions of sliding movement, said cylindrical part of said closure being perforated by an opening corresponding in size to said hole and registering therewith at one of said two extreme positions of sliding movement of said closure on said neck, said core part being provided with a hole registering with 20 said opening and permanently opening into said container by way of the bottom of said core part, said parts of said closure closing opposite ends, respectively, of said transverse hole in said neck, when said closure and neck are relatively in the 25 other one of said two extreme positions.

BRUNO VON BÜLTZINGSLÖWEN.
